CLAIM

The ornamental design for a control panel face plate, as
shown and described.

DESCRIPTION

FIG. 1 is a top perspective view of a control panel face
plate showing my new design;

FIG. 2 is a front elevational view thereof;

FIG. 3 is a left side elevational view thereof, the right
side being a mirror image;

FIG. 4 is a top plan view thereof, the bottom plan being
a mirror image; and

FIG. 5 is a front elevational view of a second embodiment
thereof, the sides, top and bottom views shown in
FIGS. 3 and 4.

The fragmentary broken line representations of a
weather simulation chamber sidewall in FIG. 1 are for
purposes of illustration only, and form no part of the
claimed design.
